A. M. MULLER

AUTOMOBILE BUMPER

Filed June 8, 1925

INVENTOR.
ALEXANDER MICHAEL MULLER

BY
Harry Schreder
ATTORNEYS.

UNITED STATES PATENT OFFICE.

ALEXANDER MICHAEL MULLER, OF OAKLAND, CALIFORNIA.

AUTOMOBILE BUMPER.

Application filed June 8, 1925. Serial No. 35,524.

To all whom it may concern:

Be it known that I, ALEXANDER MICHAEL MULLER, a citizen of the United States, residing at Oakland, in the county of Alameda and State of California, have invented certain new and useful Improvements in Automobile Bumpers, of which the following is a specification.

My invention is an automobile bumper of the single band type reversed on itself to form a loop from one side of the car to the other. An object of my invention is to provide a bumper made from a single band bent with reverse turns on itself, whereby the central part of the band extends outwardly from the car, each end is crossed over the other and connected to the front central part and the rear loops are secured to the frame of the vehicle.

Another object of my invention is to mount a ball-bearing at the sliding parts of the bumpers where the spring band would otherwise contact. As a detail of this I construct a yoke with ball races therein, adapted to engage a set of balls which bear against a spring member. I attach the antifriction yoke to the ends of the band and to the central front part of the bumper to provide for the sliding movement between the ends and the central front section of the band.

My invention will be more readily understood from the following description and drawings in which:—

Figure 1 is a front view of the bumper in the direction of the arrow 1 of Figure 2.

Figure 2 is a plan view of Figure 1 in the direction of the arrow 2, showing the attachment to a vehicle.

Figure 3 is a rear elevation in the direction of the arrow 3 of Figure 2.

Figure 4 is a transverse section of one of the ball-bearing yokes as if taken from the line 4—4 of Figures 1 to 3.

Figure 5 is a horizontal section of the yoke and bumper band taken on the line 5—5 of Figure 4.

Figure 6 is a view in vertical section of an alternate form of ball bearing yoke showing the yoke clamped tight, to one part of the bumper and the other part operating between ball bearings.

Figure 7 is a front elevation of Figure 6 in the direction of the arrow 7.

Figure 8 is a section through the bumper

holder on the line 8—8 of Figure 2 in the direction of the arrow.

My bumper as a whole is designated by the numeral 1, and is constructed with a single band of spring metal, having a front section 2 extending straight across the vehicle from one side to the other. Similar reversed bends 3 are formed in the metal strip so that the clamped sections 4 are substantially parallel to the front 2. The central portion of the back of the bumper has the bands crossed, as indicated at 5 by which the edges of the band contact. The front ends 6 of the band bear against the front section 2.

The cross-over 5 of the band is held by a screw-threaded staple 7, having a cross-bar 8 and a clamping nut 9 on each leg of the staple. It is intended by this means to secure the cross-over sections so they will not have any relative movement. Any other suitable clamp will probably be sufficient. The bumper is attached to the chassis by any suitable holder 10 having clamps 11 to engage the clamped sections 4 of which the holder shown has channel shaped straps 12 with an inturned end 13 engaging the channel 14 of the chassis.

The ball bearing yokes connecting the ends 6 of the bumper to the front section 2, are constructed as follows: In Figures 4 and 5 the yoke 15, having downwardly extending legs 16 and 17, with a clamp-bolt 18 therebetween, is rigidly secured to the ends 6 of the band by means of a bolt 19. These ends 6 have short ball races 20 and the leg 16 of the yoke has ball races 21. The balls 22 inserted in these races bear against the central section 2 of the bumper and allow free sliding movement.

In the alternative yoke, as shown in Figures 6 and 7, the yoke 25 is constructed with double reverse bends 26 and 27, forming an anti-friction bearing 28 between the arm 29 and the mid-section 30, constructed by ball races 31 in which the anti-friction balls 32 press against the central front section 2 of the bumper. The clamping section of the yoke comprises the mid-section 30 and the arm 33, between which the end 6 of the bumper is secured by the bolt 34, which extends through the arm 33 and is screw-threaded into the mid-section 30. This construction may be simplified by omitting the

reverse bend 27 and the arm 33 by bolting the end 6 of the bumper directly onto the section 30.

These anti-friction yokes function as follows: As above described, it will be noted that they are rigidly clamped to the cross-over ends 6 of the bumper and slide on the central front section. Therefore when the bumper is pressed together these yokes have an easy sliding motion on the front section. It will be manifest that the construction of the bumper itself and of the anti-friction yokes may be considerably modified.

15 Having described my invention what I claim is:—

1. A bumper comprising in combination a single band of metal bent at each side in reverse bends to form a front section and 20 rear clamping sections, the ends of the band being crossed over each other and brought into contact with the front section.

2. A bumper as claimed in claim 1, having means to hold the ends into contact with the 25 front section of the band.

3. A bumper as claimed in claim 1, having an anti-friction yoke engaging the ends of the band and the front section thereof.

4. A bumper as claimed in claim 1, having a yoke secured to the ends of the band 30 and having an anti-friction ball bearing engaging the front section of the band.

5. A bumper as claimed in claim 1, having the yoke formed with reverse bends, two sections of such yoke being clamped to the end 35 of the band and the other section of the yoke forming an anti-friction ball bearing engaging the front section of the band.

6. A bumper as claimed in claim 1, having a clamp securing the crossed over ends of the band to prevent movement thereof.

7. A bumper as claimed in claim 1, having clamps securing said clamping sections of the band to the frame of a vehicle, having a threaded staple securing the cross over 45 parts of the ends of the band and anti-friction yokes engaging the ends of the band and the front section thereof.

In testimony whereof I affix my signature.
ALEXANDER MICHAEL MULLER.
